SEWING MACHINE

Frédéric Jenni, Paris, France, assignor to The
Merrow Machine Company, Hartford, Conn.,
a corporation of Connecticut

Application January 2, 1934, Serial No. 704,985

2 Claims. - (Cl. 112—116)

This invention relates particularly to feed control in sewing machines which produce borders upon the material.

The invention is illustrated as applied to a widely known Merrow crochet machine but its use is not limited to such machines; and the objects of the invention are to facilitate the production of various designs or effects in borders; and by means of graduated scales and indicators 5 for adjustments of various parts of the mechanism to enable one to make records of the various adjustments and in order to facilitate the making of duplications of the results and give instructions for reproductions at any time to 10 those skilled in the art.

The machine about to be described forms 15 crochet stitches by the use of an eye pointed needle, a latch needle, much like a knitting machine latch needle, feeding devices and other usual accompaniments, and, with the present improvements, may produce a variety of borders from one continuous thread or from two or more threads, with the supplemental thread extending only into the enchain loops of the 20 primary thread at the outer edge of the border. The various styles or effects displayed in borders are accomplished through predetermined adjustments of the length and character of the feeding effects upon the material, the depth of the 25 stitches into the material, the sizes, qualities, colors and tensions of the thread or threads, and other conditions, hence the advantage of definite records to enable operators to produce and reproduce the desired definite results with facility.

30 In the accompanying drawings, forming a part of this specification;

Figure 1 is a front elevation of a machine embodying the invention with part of the machine frame shown in section.

40 Figure 2 is a view of a part of the machine shown in Fig. 1 with a frame cap removed to show mechanism for actuating the stitch forming implements.

Figure 3 is an edge view of a frame cap and 45 associated parts and also shows in section a pair of cam cylinders for actuating a part supported by the frame cap.

Figure 4 is a plan view partly in section of feed mechanism and that part of the machine frame upon which the feed mechanism is supported.

50 Figure 5 is an end view of part of the machine frame showing also the feed mechanism illustrated in Fig. 4, part of the machine frame being shown in section.

Figure 6 is a detail view of a feed gear with portions of associated parts, such as a cam and two cam rings, indicated in dotted lines.

Figure 7 is a sectional view on line 7—7 of Fig. 6.

Figure 8 is a sectional view on line 8—8 of Fig. 6.

Figure 9 is a sectional view on line 9—9 of Fig. 4.

Figure 10 is a diagrammatic view of stitching, 10 showing a variety of borders.

Figure 11 is a detail view of a latch hook and a portion of its carrier.

The main shaft 1 is journaled in the frame 2 and bears the driving wheel 3 with its eccentric 4 which operates through the connection 5, the needle lever 6 and needle bar 7 to reciprocate the eye pointed needle 8, as usual in sewing machines.

The grooved cam cylinder 9 is secured upon the main shaft 1 and is provided with gear teeth, 20 which mesh into similar gear teeth on the grooved cam cylinder 10, which is supported upon the shaft 11, the latter being journaled in the frame 2.

The upper grooved cam cylinder is provided with an end cam 12 to act upon a lever 13 secured to the rod 14 to oscillate the supplemental thread carrier 15 with the help of the spring 16 coiled upon the rod 14. The free end of the supplemental thread carrier 15 is thus moved to and fro below the point of the needle.

The crochet hook 17 is secured to its carrier 18, which is pivotally supported upon the sliding dove-tailed block 19, which travels in a guide-way provided by the guides 20 and 21 secured to the frame cap 22.

35 The crochet hook carrier 18 is provided with two arms 23 and 24, near the extremities of each of which is a stud carrying an antifriction cam roll, as 25 and 26.

40 Thus the crochet hook 17 is reciprocated and oscillated to move above the work, around its edge and below the work to grasp the needle thread above and below the work and interloop the thread at the outer edge of the border.

45 When a supplemental thread is used it is carried by the supplemental thread carrier 15 and is enchain with the needle thread at the edge of the border but does not penetrate the fabric.

50 The eccentric 27 is secured to the main shaft 1 and drives the eccentric connection 28, which is adjustably pivoted to the feed driving lever 29, whose forked end acts upon the pin 30 to reciprocate the feed dog 31, which is movable in a chan-

nel in the holder 32, which latter is acted upon through the medium of the tappet lever 33, bearing the tappet 34 and pin 35, to raise the feed dog into action upon the fabric or other material. The feed dog makes one reciprocation for each complete cycle of stitch forming and is adapted to be raised by any one of a plurality of cams (about to be described) into contact with the fabric while the needle is out of the fabric.

10 With the fabric engaged by the raised feed dog, the latter moves to advance the fabric but in returning it moves downward, under the effect of spring 36, to clear the fabric. The feed raising cams referred to are respectively effective for 15 feeding the material either one step for each cycle, one step for each four cycles, or one step for each eight cycles of stitch forming operations and means for quickly changing from any one to any other of these varieties include the 20 above mentioned tappet lever 33 and parts associated therewith as will more fully appear.

The feed gear 37 is rotatably supported upon the stud 38 and meshes with the pinion 39 on the outer end of the main shaft 1. The ratio of the gearing is eight to one. The large gear 25 bears cam 40 and cam rings 41 and 42, any one of which three elements may act upon the tappet 34 to raise the feed dog. The feed raising cam 40 is secured to gear 37 and is effective to engage 30 the tappet 34 and raise the feed dog and hold it in position to feed the fabric but is brought into action only once for eight full cycles of stitching, thus permitting a cluster of eight stitches to be 35 formed at substantially one place in the material and when the material is advanced the stitches at the outer edge of the cluster are spread, producing the well known shell stitch as diagrammatically illustrated at 43 in Fig. 10. The cam ring 41 is provided with two feed raising lobes 44 and 45, suitably spaced to produce four stitch shells as at 46, Fig. 10. Cam ring 42 is provided 40 with eight feed raising lobes as 47, which raise the feed dog once for each stitch cycle and produce a plain border as at 48, Fig. 10.

45 The four stitch cam ring 41 is rotatably supported on the hub 49 of the feed gear 37 and is itself provided with a hub 50, approximately the length of the thickness of the plain stitch cam ring 42 and upon which hub the latter mentioned cam ring is rotatably supported.

50 The screw 51 extends entirely through the feed gear 37 and through elongated holes in the two cam rings 41 and 42 and is threaded into the cam 40, which is held thereby, and serves to secure the cam rings when the screw is tightened.

55 The screw 52 extends through an elongated hole 53 in the feed gear 37 and engages a threaded hole in cam ring 41, the latter being thus permitted adjustment, which may be secured by tightening this screw.

60 The screws 54 and 55 extend through elongated holes in the feed gear 37 and engage threaded holes in cam ring 42, the latter being thus permitted adjustment which may be secured by 65 tightening the screws.

65 The indicator 56 (in practice stamped Q for identification and record) is pivoted upon the stud 38 and held against the face of the feed gear 37 by the screw 52. The position of screw 52, 70 established by angular adjustment of cam ring 41, also determines the angular position of the indicator 56, and as the latter cooperates with a graduated and numbered scale on the face of the feed gear, means are thus provided whereby 75 adjustment for length of feed for four stitch

shells (as shown at 46, Fig. 10) is indicated in a manner suitable for recording. Similarly the indicator 57 (in practice stamped U) is also pivoted upon the stud 38 and held against the face of the feed gear 37 by screws 54 and 55, to cooperate with a graduated and numbered scale on the feed gear for indicating adjustment of cam ring 42 for length of feed for plain stitching.

5 The tappet lever 33, carrying the tappet 34, is pivotally and bodily movable upon the stud 58 10 and its lateral position is controlled through the bar 59, having a projection 60 extending into a groove 61 in the tappet lever 33.

The bar 59 is removably secured to sliding bar 15 62, which is controlled by the lever 63 through the connection 64.

The lever 63 is provided with a pivoted latch 65, which may lock into either of the three notches in plate 66, which plate is in practice 20 stamped 1-4-8 respectively just above the notches.

When the latch 65 is in the left-hand notch of the plate 66, the tappet 34 is in its extreme left-hand position, where the lobes of the cam ring 25 42 may act upon the tappet to raise the feed dog 31 into action to feed the fabric once for every 30 stitch forming cycle producing stitching represented at 48, 67 and 68 in Fig. 10.

When the lever 63 is moved so that the latch 65 locks into the center notch of the plate 66 (in 35 practice stamped 4), the tappet 34 will be in position to be acted upon by the two lobes of cam ring 41 to raise the feed dog 31 into action to feed the fabric once for each four stitching cycles, and will then produce shells of four stitches each, 40 as shown at 46 in Fig. 10.

When the lever 63 is moved so that the latch 65 will lock into the notch stamped 8 on the plate 66, the tappet 34 will be in position to be acted upon by the cam 40 to raise the feed dog 31 into 45 position to feed the fabric once for each eight stitching cycles and produce shells as represented at 43 in Fig. 10.

The fabric edge guide 69 is adjustably secured 50 to the dove-tail slide 70 by the screw 71, which also serves as a pivotal support for the connection 72 (in practice stamped B) which is adjustably held in position upon the segment 73 by means of the thumb screw 74, which screws into a nut 55 loosely fitted into the curved slot 75.

The thumb screw 74 may be loosened and moved upward or downward to carry the fabric guide 69 further from or nearer to the needle 8 and afterward tightened to determine the depth of needle penetration from the edge of the fabric.

The pointer at the end of connection 72 indicates on the numbered scale the position of the fabric edge guide.

The primary or fundamental adjustment of the feeding is preferably made with reference to 60 the action of the feed raising cam 40 through the adjustment of the pivotal connection 76 in the slot 77 of the angle lever 29, which in practice is stamped A for identification.

The plate 78 is slidably secured to the rear side 65 of the angle lever 29 by means of the bolt 79, and bears the indicator point 80, the position of which is shown upon the numbered scale on the angle lever 29.

Having thus described my invention, what I 70 claim is,—

1. In a crochet machine having stitch forming mechanism, feeding mechanism including a feed dog and means for reciprocating the feed dog longitudinally, said reciprocating means compris- 75

5

ing elements movable relatively to each other to vary the longitudinal movement of the feed dog, a series of graduations on one of said elements, an indicator movable with the other element to denote on said graduations the variance in the relative positions of said two elements, separate means including a gear and a plurality of cams associated therewith for moving the feed dog into engagement with the work, said cams being adjustable relative to the gear to vary their effect on the feed dog, an indicator connected to and movable in unison with each of said cams, a series of graduations associated with each of said cam indicators, a tappet, a tappet lever, means for moving said tappet lever to adjust the tappet into the path of any one of said cams, means for denoting the movement of said tappet adjusting means, an adjustable fabric edge guide, an indicator movable in unison with said fabric edge guide, and a series of graduations associated with said edge guide indicator, whereby suitable adjustments may be made and definitely recorded for producing and directing the production of the results specified.

2. In a crochet machine having stitch forming mechanism, feeding mechanism including a feed

dog and means for reciprocating said feed dog longitudinally, said reciprocating means comprising a pair of elements movable relatively to each other to vary the longitudinal movement of the feed dog, an indicator movable in unison with one of said elements, a series of graduations associated with said indicator to denote the variance in the relative positions of said two elements, separate means including a gear and a plurality of cams associated therewith for moving the feed dog into engagement with the work, said cams being adjustable relative to the gear to vary their effect on the feed dog, an indicator connected to each of said cams, a series of graduations for each indicator carried by said gear, a tappet, a tappet lever, means for moving said tappet lever to adjust the tappet into the path of any one of said cams, means for denoting the movement of said tappet adjusting means, an adjustable fabric edge guide, an indicator movable in unison with said fabric edge guide, and a series of graduations associated with said edge guide indicator, whereby suitable adjustments may be made and definitely recorded for producing and directing the production of the results specified.

FRÉDERIC JENNI.
